Primary Examiner — Katherine A Holbrow
Assistant Examiner — Riya Salil Kamat(57) **CLAIM**

I claim the ornamental design for a board game, as shown and described.

DESCRIPTION

FIG. 1 is an assembled top view of the board game.
FIG. 2A is an upper left detail view of FIG. 1 of the claimed design.

FIG. 2B is an upper right detail view of FIG. 1 of the claimed design.

FIG. 2C is a bottom left detail view of FIG. 1 of the claimed design; and,

FIG. 2D is a bottom right detail view of FIG. 1 of the claimed design.

The broken lines represent the bounds of the detail views and form no part of the claimed design.

1 Claim, 5 Drawing Sheets(56)
